[57] CLAIM

The ornamental design for a clip for a baby's pacifier, as shown and described.

DESCRIPTION

FIG. 1 is a perspective view of a clip for a baby's pacifier showing our new design;

FIG. 2 is a top plan view thereof;

FIG. 3 is a side elevational view thereof;

FIG. 4 is a bottom plan view thereof;

FIG. 5 is a left hand elevational view thereof; and

FIG. 6 is a right hand elevational view thereof.

The broken line showing of the pacifier is for illustrative purposes only and forms no part of the claimed design.
